(57) **CLAIM**

The ornamental design for a beverage cartridge, as shown
and described.

DESCRIPTION

FIG. 1 is a top, front, left side perspective view of a beverage
cartridge showing our new design;

FIG. 2 is top, front, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dot-dash broken lines illustrate boundaries of the claim
and form no part of the claimed design. The dash-dash
broken lines illustrate portions of the beverage cartridge that
form no part of the claimed design.
